CLAIM

The ornamental design for a speaker enclosure, substantially
as shown and described.

DESCRIPTION

FIG. 1 is a top, front, right perspective view of the speaker
enclosure in accordance with the present invention;
FIG. 2 is a bottom, rear, left, perspective view, thereof;
FIG. 3 is a plan view of the top, thereof;
FIG. 4 is a plan view of the bottom, thereof;
FIG. 5 is an elevation view of the right side, thereof;
FIG. 6 is an elevation view of the left side, thereof;
FIG. 7 is an elevation view of the front side, thereof; and,
FIG. 8 is an elevation view of the rear side, thereof.
The broken lines depict portions of the speaker enclosure
that form no part of the claimed design.

1 Claim, 3 Drawing Sheets
